UNITED STATES PATENT OFFICE.

PAUL M. BUSICK, OF MEMPHIS, TENNESSEE.

DESIGN FOR A BOOTH.

58,423.

Specification for Design.

Patented July 19, 1921.

Application filed January 19, 1920. Serial No. 352,627. Term of patent 14 years.

To all whom it may concern:

Be it known that I, PAUL M. BUSICK, a citizen of the United States, residing at Memphis, in the county of Shelby and State of Tennessee, have invented a certain new, original, and ornamental Design for Booths, of which the following is a specification.

Said design relates to stands or booths that are adapted particularly for location in public parks and along driveways, for the sale of refreshments, such as soft drinks, fruits, candies, confections, pastries, etc., and consists of the ornamental arrangement,

construction and style as shown in the accompanying drawing.

What I claim is:

The design for a booth as herein shown and described.

In witness whereof, I have hereunto set my hand and seal at Memphis, Tennessee this third day of January, A. D. nineteen hundred and twenty.

P. M. BUSICK. [L. S.]

Witnesses:

JOHN W. FARLEY,
F. M. BAILEY.
